PUMP AND VALVE STRUCTURE

Robert A. Shields, Bloomsburg, Pa.

Application March 24, 1948, Serial No. 16,772

5 Claims. (Cl. 103—178)

1

This invention relates to pumps in general and in particular to small pumps that may have to pump liquid and gas under fairly high pressure and operate at high speed.

The ordinary type of reciprocating pump can not operate efficiently at high speed and pump both gas and liquid, for the simple reason that the gas will be compressed and immediately expand on the intake stroke and prevent the piston pulling in more liquid or gas. This is particularly true where the liquid being pumped is gasoline or other fluid which will boil readily upon reduction of pressure. Small rotary pumps have been built which can handle the liquid and gas but are extremely expensive, particularly where they must develop a relatively high exhaust pressure. Reciprocating pumps which are designed to handle small quantities of liquid under high pressure require extremely close tolerances with the result that the price becomes prohibitive, particularly where the amount of liquid pumped varies as in an internal combustion engine using fuel injection. It is an object, therefore, of the present invention to provide a constant displacement reciprocating pump which can handle either vapor or liquid alone or combined.

A further object of the invention is the provision of a small high speed high pressure pump having valve structures immediately responsive to change in pressures so as to close the inlet and outlet ports even at high speed.

A still further object of the invention is the provision of a small high pressure high speed pump which can handle varying amounts of liquid, yet which does not require expensive machine work to construct.

A yet further object of the invention is the provision of a pump having the inlet valve and piston head formed integral.

These and other objects of the invention will be apparent to persons skilled in the art from a study of the following description and accompanying drawings, in which:

Fig. 1 is a sectional view taken through the improved pump structure;

Fig. 2 is a sectional view similar to Fig. 1 but showing the pump on the intake stroke at the left hand side of the figure and on the exhaust stroke at the right hand half of the figure, and

Fig. 3 is a sectional view similar to Fig. 1 but showing a modification.

Referring now to the drawings in detail, it will be seen that the pump is formed in general of a housing A, cylinder structure B and piston struc-

2

ture C. The housing structure A is generally cylindrical in form, having an outer wall 2, a top wall 4 and bottom wall 6. The top and bottom walls are bored to provide opening 8 for reception of the cylinder structure B. The bottom wall 6 is drilled and adapted to receive a fitting 10 in which is soldered or otherwise secured a discharge pipe 12. The upper wall 4 has a shoulder thereof adapted to receive a bushing member 14 by means of which the cylinder and piston assembly may be clamped into the housing A.

The cylinder structure B is of cylindrical form having its central portion bored out as at 16 to form the cylinder walls and the top part is counterbored as at 18 to permit insertion of compression spring 20, the bottom end of which rests upon the shoulder formed by the counterbore. The bottom 22 of the cylinder has bored therein a small passage 24 from which a plurality of small passages 26 radiate outwardly and downwardly, thus forming the exhaust passages from the cylinder. A portion of the bottom is bored to provide a recess in which the discharge valve 28 may be placed. This valve is preferably made of a synthetic rubber or other resilient material having its edges only cemented to the cylinder in an annular area outside of the area in which the passages 26 pass through the bottom wall. A small passage 30 is punched or otherwise formed in the central part of the valve structure 28. In order to provide space into which the valve structure may deflect, a resilient washer 32 is placed between the valve and the housing bottom and will be tightly clamped onto the bottom by means of the bushing 14 bearing on the top edge of the cylinder. Cylinder inlet ports are provided by boring straight through the cylinder as at 34.

The piston structure C is formed with a head portion 36 adapted to be struck by a cam or other operating part to cause inward motion of the piston under the power stroke. Inwardly of the operating head surface a shoulder 38 is provided which is adapted to strike the overhanging lip 40 of the bushing 14 and thereby limit the outward stroke of the piston under compression of the spring 20 which bears at its upper end upon the inner surface of the shoulder 38. The lower portion of the piston is machined to provide a surface 42 having fairly close engagement with the cylinder walls 16. A passage 44 is bored upwardly in the piston for the purpose of receiving a plug member 46 driven, pressed or shrunk into the passage 44. This plug 46 is pro-

vided with upper and lower transverse or radial passages 48 and 50 respectively joined by an axial passage 52. The lower end of the plug is machined away slightly so as to provide a clearance 54 between the plug and passage 44 in the region of the transverse passage 50. A piston inlet supply passage 56 is bored radially through the piston and in order to supply fluid to this passage the piston has a groove 58 cut therein to provide clearance between the cylinder walls and piston in the zone of the transverse passage 56, thus irrespective of the position of the piston in the cylinder, fluid or other matter can enter the piston from cylinder port 34. A combined inlet valve and piston end member 60 is provided and this member is preferably made of resilient, synthetic material cemented or otherwise secured to the annular area of the bottom end of piston structure C. The inner central area of this valve and piston member 60 will be free of connection to the plug 46 and is provided in its central portion with an inlet passage 62. The resilient member 60 is compressed slightly against the walls of cylinder 16 and will effectively seal against any leakage of liquid or vapor along the cylinder walls.

In operation the piston operating head will be moved inwardly and outwardly at a fairly high rate of speed causing the piston and valve member 60 to oscillate between the full line position of Fig. 1 and the full line position at the right hand side of Fig. 2. During the downward stroke the gas or liquid beneath the piston member 60 will be forced through the passages 24 and 26 and against the flexible member 28. Pressure of the fluid or vapor against the member 28 will cause the same to deflect as shown in the right hand half of Fig. 2 and the fluid and vapor can discharge from the passages out through passage 30 in the valve member. Immediately upon the commencement of the backward stroke of piston structure C the valve member 28 will seat due to the natural resiliency of the material and due to the pressure existing in pipe 12. Upward movement of the piston will cause fluid or gas in housing A to flow through the passages 34 in the cylinder into clearance 58 and passages 56 in the piston. From 56 the fluid or gas will flow through passages 48, 52 and 50 into clearance space 54. This will cause the resilient piston structure and valve member 60 to deflect as shown in the left hand portion of Fig. 2 and the fluid or gas can flow through central passage 62 into space beneath the piston end. Since the pump is of constant displacement, it will be understood that liquid or gas will be supplied to the reservoir R in housing A by means of an inlet passage 64 at a varying rate, thus since the pump is supplied with liquid at a varying rate, its discharge will be at a varying rate, even though the stroke and speed are constant. The pump will handle both liquid or gas or a combination of both, since the clearances between the piston and cylinder are substantially zero at the bottom end of the stroke and the small amount of gas retained in passages 24 and 26 is so small with respect to the pump displacement that they cannot expand sufficiently to block admission of liquid or gas upon the intake stroke of the pump. Furthermore, the volume of passage 62 will be decreased due to the flow of the material under compression thereby more nearly giving zero volume at the bottom of the stroke.

In some cases it may be found considerably cheaper to manufacture the piston as shown in

Fig. 3. In this form the cylinder structure is in general identical with that described in Fig. 1 and accordingly the same reference characters have been used and it is to be understood that the cylinder is clamped in the housing in exactly the same manner as is the cylinder of Fig. 1. The only modification of the cylinder structure in this figure is that the exhaust ports or passages 70 extend vertically through the bottom of the cylinder instead of radially and vertically as do the passages 24 and 26 of Fig. 1. In this manner the volume of the outlet passages is further reduced and the efficiency of the pump is slightly increased. The piston shown in Fig. 3 will have its upper end constructed exactly as shown in Fig. 1 but will be cut off immediately below the passage 56, thus leaving the plug 46 extending outwardly from the piston. In order to seal the piston with respect to the cylinder synthetic rubber or other resilient material 72 is vulcanized or otherwise adhered to the outer walls of plug 46 and to the inner walls 16 of the cylinder B, thus the resilient material will act in shear during the movement of the piston, but being permanently locked to the cylinder and plug 46 will positively prevent any flow of liquid out of the pump chamber along the cylinder or piston surfaces. In this manner it is not necessary to carefully watch the machining of the parts and the cost of production will be materially reduced. The resilient material 72 caps the end of the plug 46 but is not adhered thereto, thus permitting the fluid or gas to flow exactly as that described in connection with Fig. 1, that is, fluid and gas can enter from clearance space 54 into the pump chamber 74 through the opening 76 formed in the combined piston and valve structure. With this structure as in that of Figs. 1 and 2, the resilient material of both the inlet and outlet valves will deflect to permit entrance or escape of matter into or from the pump chamber 74. Likewise, due to the use of the resilient material, the piston can directly contact the bottom wall of the cylinder and thus reduce the pump displacement space or chamber to zero on the exhaust stroke.

While the invention has been described more or less in detail with specific reference to the accompanying figures, it is to be understood that various modifications and rearrangements of parts may be made without departing from the scope of the invention as defined by the following claims.

What is claimed is:

1. A combined pump and valve structure comprising a cylinder having one end closed, a discharge passage extending from the interior of the cylinder through the closed end, a piston reciprocable in the cylinder during intake and discharge strokes and having portions of its sides spaced from the cylinder, an intake passage extending through the piston, non-metallic resilient material overlapping the entire inner end of said piston and filling the space between said piston portion and cylinder wall, said material being adhered to the cylinder wall and piston sides and acting in shear during reciprocation of the piston, and an intake passage continuation extending through said material in offset relation to said first-named intake passage, said resilient material having portions thereof bowing inwardly from the inner end of said piston to admit matter through the intake and intake continuation into the cylinder beneath the piston and material during the intake stroke of the piston.

2. A combined pump and valve structure com-

prising a cylinder having one end closed, a discharge passage extending from the interior of the cylinder through the closed end, a piston reciprocable in the cylinder during intake and discharge strokes, said piston including a plug part 5 pressed into the upper portion of the piston and having projecting sides spaced from the cylinder wall and also having its lower end reduced in diameter, interconnected axial and radial intake 10 passages extending through the piston and plug part and one at least terminating at the reduced diameter end of said plug part, resilient material filling the space between said piston plug part and cylinder wall and being connected to said plug part, said material capping the end of said piston plug part and spaced from the reduced end thereof to provide annular clearance space between said 15 resilient material and plug part connected to said intake passages, and an opening in said resilient material substantially on the axis of said piston plug part, said resilient material capping the end of said piston plug part flexing during the intake stroke to pass matter beneath the piston and material from said intake passages annular space and openings during the intake stroke of said 20 piston.

3. The structure of claim 2 characterized in that said resilient material is connected to the cylinder wall and acts in shear during reciprocation of the piston.

4. A combined pump and valve structure comprising a cylinder having one end closed, a piston reciprocable in the cylinder during intake and discharge strokes and having a portion of its sides spaced from the cylinder wall, an intake 30 passage extending through the piston, non-metallic resilient material covering the end of said piston and filling the space between the sides 35

thereof and the cylinder wall, said material being of sufficient thickness as to contact substantially the entire inner surface of the closed end of the cylinder at the end of the discharge stroke, a discharge passage extending from the interior of the cylinder through the closed end, non-metallic resilient material contacting the outer side of said closed end in an area surrounding the discharge passage, openings formed in said material out of alignment with said discharge and inlet passages, said resilient material adjacent the openings bowing away from the piston end and end wall of the cylinder to pass matter during the intake and discharge strokes respectively, and said first-named material being bonded to said piston and cylinder and acting in shear during reciprocation of the said piston.

5. The structure of claim 4 characterized in that said last-named resilient material is adhered to said cylinder closed end in an annular area surrounding said discharge passage and opening.
